CALL RECORDING DEVICE

Adolph F. von Soden, Los Angeles, Calif., assignor
of one one-thousandth to Corey R. Cheney,
Long Beach, Calif.

Application November 23, 1938, Serial No. 242,004

3 Claims. (Cl. 179—5.5)

My invention relates to telephone incoming call or code recording devices and more particularly to the novel form of call recording instruments, adapted for recording and registering all such incoming calls which may come in through the telephone of the subscriber or user during his absence.

Manifestly, an object of my invention is to provide a simple and inexpensive telephone call or code recording device or instrument, consisting of suitable receiving amplifying and recording means which will send out and receive electrical impulses corresponding in variety and intensity produced within the instrument wherein such variations occur, so that the difference of impulses received or created within said instrument, may be permanently recorded.

Another object of my invention is to provide suitable combined sending and receiving set or apparatus which may be positioned in close proximity to the standard or conventional telephone system, said apparatus being provided with suitable diaphragm adapted to be actuated by the ringing sound of the telephone bell, so that, by the vibratory action of said diaphragm, a contact within said apparatus may be established and maintained.

Another object of my invention is to provide said apparatus in combination with a set of suitable current actuating cells, such as selenium cells or the like, to which suitable galvanometers are attached, so that, the flow of the electrical current passing into and therefrom, may be recorded and registered upon said galvanometers.

A further object of my invention is to provide said apparatus in combination with a set of suitable code recording means, operable by said flow of the electrical current passing through said galvanometers, so that, the difference of potential energy, adapted to actuate correspondingly said galvanometers may be registered and recorded, in terms of suitably arranged numerical values, representing variations of numerical digits, which are recognized as a special or selectively arranged set of numbers, corresponding to the station number, wherefrom the message was to be forthcoming or the telephonic contact was intended to be established.

A further object of my invention is to provide an apparatus having in combination a suitably arranged housing which is equipped with an instrument such as a clock or the like, having therein a set of suitably arranged means adapted to be used for transmitting and receiving variations of electrical impulses created therein, thus

establishing the contact between the telephonic points as evidenced by the sound of the ringing bell, also, having the current flow transmitting means attached thereto, which may, if so desired, be in contact with the telephone wires, or, it may be positioned within close proximity of the telephonic system between certain stations and between which the telephonic contact is sought to be established and further, having suitable means adapted to operate said device at a speed and intensity which may be regulated to correspond to the time required for said contact to be established and registered, also in addition, having suitable means or a set of means adapted to permanently record said transmitted electrical impulses created and recorded by the said recording means within said apparatus.

Further objects and advantages of my invention as will hereinafter more fully appear, I attain by the construction herein shown on the drawing and described in the specification forming a part of my application.

Reference is had to the accompanying drawing, in which the similar reference characters denote the similar parts.

In the drawing:

Fig. 1 shows a perspective view of a telephonic and recording apparatus, having the contact establishing system in combination therewith.

Fig. 2 shows a diagrammatical illustration of the establishing, the contacting and the recording circuit, of my invention.

Fig. 3 shows a fragmentary view of the tape, upon which the incoming calls are recorded.

Fig. 4 shows in dotted lines, the actuating cells, of the called number or station.

Describing my invention more in detail, said invention comprises a housing, generally designated by numeral 2 which is equipped with suitable receiver 4 having a microphone 6 positioned as shown, also having suitable selectors 8 protruding therefrom at one side, further, having a suitable electric clock member 10 positioned therein which is energized by means of the electric current passing therethrough and through the line 12 connecting a suitable plug or switch member 14.

The clock member 10 is connected to said apparatus for the purpose of registering the time and since the outside current is required to operate the electric circuit, therefore said switch 14 may, if so desired, be connected to the source of electrical energy produced by a suitable generator 16 which provides the entire circuit set

of circuits with the necessary electric current, through the lines 18 and 19 respectively.

Said housing 2 is also provided with a suitable electrical contact switch 20 operable by means of a lever 22 and supported in action by said receiver 4 which closes the energizing circuit of the transformer 24 and the adjustable resistance 26 also, connecting the inductance 28 and the audion lamp 30 of the synchronous system 32, the operation of which will be presently described.

Said microphone 6 is connected to the circuit system by means and through the amplifying means 38 and the modulating means 36, which is provided with lead wires 40 for connecting the condenser 42 and the receiver 4 wherein one of said lead wires 40 leads into the contact establishing system 44 set in series as shown and connecting the wire 48 including the lead wire 46 respectively.

The current, passing from the electric generator 16 and through the lead wire 48, energizes the audion lamp 40, to which inductance 50 and the transformer 52 is connected, also, connecting the adjustable resistance 54 with the circuit by said lead wire 46, which connects the inductive resistance 56 together with the condenser 58 in closing and completing the circuit, thus energizing the inductive resistance 60 operable selectively by means of movable core members 62 and regulated by means of said selectors 8.

The inductive resistance 60 may be adjusted selectively, or in series, by means of said core members 62 which are held in place by said lever or the selector 8, allowing only certain amount of electrical current to pass therethrough, correspondingly energizing a set of photo-electric cells 70, shown in dotted lines, see Fig. 4, representing an outside or the receiving station and which in construction and arrangement are identical to the set or system 32 and also corresponding in number to the sending or a contact station, as shown.

Another set of the photo-electric cells 71 receive their electric current through the lead wire 72 leading from the audion lamp 30 to which suitable solenoid coil members 74 are connected and which are adapted to selectively draw the iron core members 76 within said coils 74, while and when the electric circuit is completed through the lead wire 78 and the inductive resistance 80 including the condenser 82 leading into the line 84.

Said iron core members 76 comprise non-conductive brackets 86 which are provided with bushings 88 mounted upon a common shaft member 90, as shown, said bushings 88 are provided with suitable extensions and rim sections 92 upon which letters and numbers are set or cut, also having contacting individual switches 94, the purpose of which will be presently described.

When the electric current passes through the photo-electric cells 71 establishing its intensity or volume, the solenoids 74 draw the core members 76 into a selective position, which causes said rim sections 92 to be set at certain designated points or places in readiness for an imprint upon the paper tape 96, which is supported and held in place by means of the plate member 98 mounted upon a suitable lever 99, pivoted as at 100 and operable by means of the magnetic coil 102 energized by the electric current passing through the wires 104 and 84 respectively, when the switch 106 is closed.

The electric generator 16 supplies its energy to the circuit by means of the lead wires 108 and 110 respectively, of which the wire 108 connects the synchronous system 32 by means of said wire 112 and through the rheostat 112 wherein the wire 110 provides means for closing the electric circuit through the switch 114 by means of the lead wire 116.

The electric circuit is also provided with suitable contact diaphragm 116 of which the plate 118 may, if so desired, be the face plate of said clock 18, said diaphragm 116 receiving its contact through the wires 110 and then by means of the wire 120 contacting the mercury balance switch 122 which is pivotally connected as at 124 and adapted to close the electric circuit by means of the lead wires 126, as shown.

The lead wire 128 is connected with a suitable electric motor 128 by means of lead wire 130, closing the electric circuit by means of the wire 132 leading into the supply wire 134, so that, when the diaphragm 116 closes the electric circuit by means of the contact points 134, the motor 128 begins its function, causing the shaft 136 and the cam 138, including the pulley 140 to revolve which drives the control pulley 142 mounted upon a suitable shaft 144 and upon which said paper tape 96 is mounted and which supplies the paper tape, during the operation of the mechanism.

Said cam 138 is provided with a raise 146 and a lobe 148 for causing the lever 150 to pivot about the pivot point 152, which is supported by means of the spring 154 of which, one end is provided with a roller 156 and the other end is equipped with extension rod 158 connecting the mercury switch 122, as shown.

When the roller 156 engages the cam surface 150, the switch 122 closes the electric circuit through the lead wires 126, then when the lobe 148 causes the roller 156 to close the switch 156 the passing electric current, through the wire 108 and 84, energizes the magnetic coil 102 and in completing the cycle through the wire 104 causes the plate 98 to press the tape 96 against said rim members 92, thus registering their position, also, when the contact is established through either of said switches 94 of the synchronous system 32, then the current passing from the line 108 into the contact line 162 and thence passing through said switches 94, will complete the electric circuit by means of the wires 164 and 166 respectively, thus causing the ringing of the bell member 168.

When the bell member 168 produces vibration or sound by means of ringing, said sound vibrations cause the diaphragm 116 to function by closing the contact points 134 which in turn causes the electric current to pass into the mechanism, energizing it, and thereby causing the photo-electric cells 70, of one station to which the call is sent, to respond in accordance with the intensity of electrical energy, which is allowed to pass through said set of inductive resistance 60, of the other or sending station.

Therefore, when the receiver 4 is not removed, the contact through the switch 20 remaining open or broken, allows the rheostat 112 to be adjusted by means of suitable push button 118 or the like, such as lever, thus causing greater amount of electrical energy to pass through the said resistance 60 and the said photo-electric cells 70, intensifying and stabilizing the respective positions of the said core member 76 operable in conjunction with the photo-electric cells 71, so

that, when the lobe 148 in its rotary movement, will close the switch 106, allowing the electrical energy to pass through the system for energizing the said solenoid 102, which will cause the plate 96 to press the paper tape 94 against the numerical imprints and thus recording the calling number, or message.

It may be noted that the apparatus for recording the incoming calls may, if so desired, be provided with a pair of sets, comprising said photo-electric cells 70 and 71, of which, one set is for receiving and recording the passing electrical impulses which is sent by the sending station, while the other is for sending the said impulses at a definitely established intensity or pressure to the other which is the receiving station of the system and wherein said impulses are sought to be established when the receiver and the switch 20 is closed, said current passing into the set which is the receiving and sending system and is completing its circuit through the ground and delivered by means of the said generator 16.

From the description herein disclosed, it may also be noted that the electrical current or currents passing through the system and substantially through the ground while synchronously established within said cells, is thoroughly insulated so as to prevent an outside interference and which is due to the fact, that the sending station combined set is energized differently, there never being two stations alike and therefore, preventing so called tapping or interfering during conversation, or interfering with code messages.

Therefore, while I have thus described my invention with great particularity, it will be clear that the same may be modified throughout a wide range I accordingly do not propose to be limited to the exact details of construction herein shown and described but reserve the right in practice to make such modifications and changes, which may come within the scope of the appended claims.

I claim as my invention:

1. In a telephone calling number recording device, a sound diaphragm, an electric circuit contact means connected with said sound diaphragm for closing the electric circuit contact and to energize said recording device, a ground contact means connecting said electric circuit contact means, a printing means energized by said sound diaphragm and actuated by the passing current passing through said electric circuit contact means for printing the incoming calling numbers, a plurality of photo-electric cell means associated with said sound diaphragm and said printing means and energized by the passing electric current for sending out and receiving the electrical impulses passing through said electric circuit contact means so that the electric current in its intensity which corresponds to the respective number or digit may be printed and recorded, and source of electric current supply connecting said recording device for supplying the electric current into said electric circuit con-

tact means, of said device, substantially as described.

2. In a code calling number recording device of the class described, an electric circuit, a source of electrical current supply, a ground contact means connecting said electric circuit, a sound diaphragm contact means connected in said electric circuit and adapted for closing said ground contact means and for energizing said recording device, a set of printing means actuated by said sound diaphragm contact means and energized by the passing electrical current for receiving and for printing the incoming calling code numbers, a set of photo-electric cell means associated with said electric circuit and said printing means for actuating each printing means independently of the other, a set of galvanometer means associated with said photo-electric cell means and said electric circuit for controlling the electric current pressure passing into each of said printing means, and contact switch means associated with said electric circuit for controlling the passage of the electrical current passing through said electric circuit of said recording device wherein said code calling numbers are to be recorded and for recording and printing same when said ground contact means is established, substantially as described.

3. In the recording devices of the class described adapted for sending out and receiving the call numbers or the like, each device performing as a separate unit or station and each having a ground contact connecting each device independently of the other, each comprising a sound diaphragm means, an electric circuit means associated with said diaphragm means adapted for energizing said recording device by the sound vibrations produced therein and caused by the sound of the bell, a source of electrical supply, an electric contact means associated with said sound diaphragm means for establishing an electro-magnetic contact between said sending and the receiving unit or station, a set of photo-electric cell means associated with said electric circuit means, a set of printing means associated with said photo-electric cell means, a set of galvanometer means connected independently with each of said printing means and said photo-electric cell means for controlling the pressure of the electric current passing therethrough and for actuating said printing means when said electric current in said photo-electric cell means is established, and contact closing means associated with said electric circuit means and said ground contact of each recording device and energized by the sound vibrations produced in said diaphragm means for closing said electric circuit between each unit or station and thereby preventing an outside interference while said units or stations are in communication and while sending, receiving, printing or recording said call numbers, substantially as described.

ADOLPH F. VON SODEN.
